ATTORNEYS.

UNITED STATES PATENT OFFICE.

PETER DOWD, OF GLOBE, ARIZONA.

MOSQUITO-MASK.

1,342,277.

Specification of Letters Patent.

Patented June 1, 1920.

Application filed February 12, 1919. Serial No. 276,553.

To all whom it may concern:

Be it known that I, PETER DOWD, a citizen of the United States, residing at Globe, in the county of Gila, State of Arizona, have 5 invented certain new and useful Improvements in Mosquito-Masks; and I do hereby declare the following to be a full, clear, and exact description of the invention, such as will enable others skilled in the art to which 10 it appertains to make and use the same.

This invention relates to new and useful improvements in protecting devices used for preventing attacks of flies and mosquitoes while the person is asleep, or when walking 15 or sitting in a place infested with such insects.

One object of the present invention is to provide a novel and improved device which is in the form of a mask, adapted to be 20 worn over the head and face of the person to prevent attacks of mosquitoes, flies, or other pests.

Another object of the present invention is to provide a novel and improved device of 25 this character which is simple in construction, easy to operate, and which can be folded into a flat and compact condition when not in use.

Other objects and advantages will be apparent from the following description when taken in connection with the accompanying drawing.

In the drawing:

Figure 1 is a perspective view of the device in open or extended position.

Fig. 2 is a plan view of the device in folded position.

Fig. 3 is a bottom plan view of the device in open position.

Fig. 4 is an enlarged perspective view of the interlocking portions of the arched members.

Fig. 5 is a perspective view of a modification of the device which is to be worn 45 while walking or sitting.

Referring particularly to the accompanying drawing, 10 represents a wire ring in four equally spaced points of which there are formed the kinks which result in the 50 radially extending portions 11. A pair of arched wire members 12 and 13 are provided at their terminals with eyes 14 which are movably engaged with the radial portions 11, whereby said members are capable 55 of being swung down so as to lie in superimposed relation on the ring 10, when the

device is folded and not in use. In the upper intermediate portion of the member 12 there is formed a downwardly extending kink 15 into which the corresponding 60 but upwardly extending kink 16 is arranged to be snapped, when the device is in set up or operative position. A piece of fine meshed mosquito netting, either of cotton, silk, metal or other suitable material, is secured at its marginal edge around the ring 10, while the dome portion is unattached with respect to the arched members, whereby said members may be easily swung into and out of folded position, without interference of the netting. 70

Secured to and depending from the edge of the ring is a fabric skirt or curtain, shown at 17, which is adapted to rest on the pillow and the person of the sleeper, to prevent the 75 insects from getting under the ring 10 and attacking the neck and face of the sleeper.

There is thus provided a novel and simple, as well as cheap device, whereby the sleeper is effectively protected from the attacks of 80 mosquitoes, flies, or other insects.

Referring particularly to Fig. 5 there is shown a modification of the device wherein 85 18 represents an adjustable band which is arranged to be engaged around the head of the wearer. Extending radially outward from the band are short wires 19 to the outer ends of which there is secured a second band 20. Secured to this band and extending upwardly over the wearer's head is a wire or cloth screen fabric 21, while depending from the band 20 is a wire screen 22 which covers the lower portion of the head and face of the wearer. To the lower edge 90 95 of the screen 22 is attached a depending fabric 23 provided with a draw string 24 for securing the same around the neck of the wearer and to prevent the insects getting within the mask.

The band 18 may be in the form similar to that of a hat band, or may be extensible to fit different sized heads. Also the extensible band may have elastic or spring wire members to hold it in different adjusted 100 105 positions.

What is claimed is:

A mosquito mask comprising a band formed from a length of metal and bent at a number of diametrically opposite points to 110 provide inwardly extending and headed projections, a pair of arched members having

their ends formed with eyes which receive opposite projections and on which projections the arched members are arranged to pivot, the intermediate portion of one of the 5 arched members being formed with a kink into which the intermediate portion of the other arched member is arranged to snap, and a netting secured to the band and ar-

ranged to be held in dome-shaped formation by the arched members.

In testimony whereof I affix my signature in the presence of two witnesses.

PETER DOWD.
